UNITED STATES PATENT OFFICE.

FRED A. PUTNAM, OF MELROSE, MASSACHUSETTS, ASSIGNOR TO MARKEM MACHINE COMPANY, OF BOSTON, MASSACHUSETTS, A CORPORATION OF MASSACHUSETTS.

METHOD OF MAKING PRINTED IMPRESSIONS.

1,314,211.

Specification of Letters Patent. Patented Aug. 26, 1919.

Application filed January 6, 1917. Serial No. 141,011.

To all whom it may concern:

Be it known that I, FRED A. PUTNAM, a citizen of the United States, residing at Melrose, county of Middlesex, State of Massachusetts, have invented an Improvement in Methods of making Printed Impressions, of which the following description, in connection with the accompanying drawing, is a specification, like characters on the drawing 10 representing like parts.

This invention relates to an improved method or process of making a printed impression, and has for its object to provide an improved method by which half-tones and 15 similar printed impressions can be successfully made on paper which is more or less soft and spongy.

Heretofore, it has been considered as impracticable to make a printed impression 20 of the order of a half-tone on paper of a spongy nature having a relatively soft or porous surface because the half-tones of a printed impression of this sort become obliterated, thus producing a very inferior 25 print. Accordingly it has been the practice to use paper having a relatively smooth or hard surface when good half-tones are desired. By my improved method, however, I can produce a satisfactory half-tone on 30 paper which is of a soft or porous nature.

I accomplish this object by first subjecting the portion of the paper on which the half-tone or other impression is to be made to the action of a heated smoothing die which 35 compacts the portion of the paper with which it contacts and produces thereon a hard smooth surface, and then I make the printed impression on this prepared portion of the paper. In thus preparing the portion 40 of the paper which is to receive the printed impression, I will preferably so treat it that the surface thereof will be depressed below the surface of the unprepared part of the paper so that the printed impression 45 will be made on a sunken portion of the paper. I will also preferably make the printed impression while the prepared surface of the paper is still warm from the effects of the heated die because by this

means the ink constituting the printed impression is more quickly dried.

In order to give an understanding of my invention, I have illustrated in the drawings more or less diagrammatically some of the steps by which the process is carried out, 55 and I will now proceed to describe such drawings and then point out the novel features of the invention in the appended claims.

Figure 1 of the drawings is a view illustrating the preliminary treatment to which the paper is subjected;

Fig. 2 is a view showing the paper treated by the heated smoothing die;

Fig. 3 is a sectional perspective view of a 65 piece of cardboard or similar paper after having been treated;

Fig. 4 illustrates the step of making the printed impression;

Fig. 5 is a view of the paper with the 70 printed impression thereon;

Fig. 6 illustrates the manner in which a plurality of sheets of paper or other material which have been printed in accordance with my process may be stacked up without danger that the printed impressions will become 75 smooched.

In the drawings, 1 indicates a sheet of cardboard, paper or other material on which the printed impression is to be made. My 80 invention is best applicable where the sheet 1 is rather thick like cardboard, although the invention can be practised equally well on paper of any thickness. I wish it understood, therefore, that the thickness of the 85 paper is not important to the invention.

As stated above, the sheet 1 is subjected to the action of a heated smoothing die before the printed impression is made thereon so as to produce a hard smooth surface on the impression-receiving portion of the paper. This operation is shown in Fig. 2 wherein the paper 1 is illustrated as being supported on a table or support 2, and 3 indicates more or less diagrammatically the heated smoothing die. This die is formed with a smooth face 4 of a size to cover the portion of the paper on which the impression is to be made.

The die may be heated in any suitable way. I have illustrated an electrical heating unit 5 for this purpose, but this is merely for the sake of illustrating the heating operation 10 and not for the sake of importing any limitation into the invention.

The heated die 3 is pressed against the face of the paper 1 with considerable pressure with the result that the portion 6 of the 15 surface of the paper with which the die comes in contact is sunk below the face 7 of the paper. The heat of the die together with the pressure not only compacts the paper with which the die has engagement, 20 but also smooths the face thereof so that the portion 6 of the surface of the paper will have a smooth, hard finish.

I find from experiments that when cardboard or similar material that has a rather 25 rough or porous surface is thus subjected to the action of the heated die, the portion of the surface of the paper with which the die contacts will be rendered relatively smooth and hard.

In treating some kinds of paper, it may 30 be desirable to moisten the surface of the paper before applying the heated die. This step is illustrated in Fig. 1 wherein 8 indicates a roll of absorbent material, such as 35 felt, which is moistened with water, or some similar liquid, and is passed over the face 7 of the paper 1, thus applying a proper amount of moisture thereto.

In treating some kinds of paper, I find 35 that a better finish can be secured by the application of the heated die when the surface of the paper has first been moistened. I wish it understood, however, that this 40 moistening process is not an essential step under all circumstances.

After the portion 6 of the surface of the paper has thus been treated and preferably 45 while the paper is still warm from its contact with the heated die, I will make the printed impression thereon. This step is 50 illustrated in Fig. 4 wherein 9 indicates an electrolyte or other block adapted for making a printed impression, which after being inked has been placed in contact with and 55 presses against the prepared portion 6 of the surface of the paper. This step of printing from the block 9 may be accomplished in any suitable printing machine and in any usual manner. This results in making the 60 printed impression as illustrated at 10 in Fig. 5 on the prepared depressed or sunken portion 6 of the surface of the paper. The advantage of making the printed impression on the paper while it is still hot is that the 65 heat of the paper operates to assist the drying of the ink. I find from experiments that where the printed impression is made on this heated-prepared surface, it is possible to handle the printed sheets 1 freely immedi-

ately after the impression is made without 65 danger of smooching or marring the printed impression.

In forming the prepared surface 6, I will 70 preferably employ a die which is so formed as to raise some portions of the surface of the paper above the normal surface 7. These raised portions will preferably be situated at the marginal portions of the depressed or sunken portions 6. As illustrative of one embodiment of this idea, I have 75 shown the die as provided with the groove 11 near its periphery. When the paper is subjected to the pressure of the heated die, some portion of the paper will be forced into the groove 11, thus forming a rib 12 which 80 surrounds the sunken portion 6. I will preferably make the groove 11 of such a depth that the face of the rib 12 will stand slightly above the untreated surface 7 of the paper. The advantage of this construction 85 is that when the sheets 1 are superposed one on the other as illustrated in Fig. 6, the ribs 12 act as spacers to hold the sheets separated, and thus are instrumental in preventing the 90 printed impression of any sheet from coming in contact with the adjacent sheet when the sheets are piled up.

This raised portion 12 need not be continuous and it may be situated at any desired portion of the sheet.

95

My improved method can be carried out on various machines and for this reason, I have chosen not to designate any particular organized machine. The process can also be practised in making printed impressions on 100 a great variety of material.

I claim:

1. The steps in the process of making a printed impression on sheet material which consist in subjecting the impression-receiving portion of said sheet to the action of heat and to a smoothing pressure which densifies the material in said portion and renders said portion of the sheet thinner than other portions not so treated and then printing the 110 impression on said prepared densified portion.

2. The process of making a printed impression on sheet material which consists in moistening the face of the sheet on which the printed impression is to be made, subjecting the impression-receiving portion of said face to heat and pressure by means of a heated die whereby said portion is densified and rendered thinner than other portions 120 not so treated and then printing the impression on said prepared densified portion.

3. The steps in the process of making a printed impression on a sheet which consist in first sinking the impression-receiving 125 portion of the surface of the sheet below the other portions of said surface and rendering said sunken portion hard and firm and then

making the printed impression on said prepared sunken portion.

4. The steps in the process of making a printed impression which consist in first 5 sinking the impression-receiving portion of a sheet on which the printed impression is to be made below the other portions of said sheet and simultaneously heating said

sunken portion and rendering the surface thereof smooth and firm and thereafter 10 making the printed impression on the heated, smooth, sunken surface.

In testimony whereof, I have signed my name to this specification.

FRED A. PUTNAM.
